UNITED STATES PATENT OFFICE.

ADOLPH MUELLERWIESS, OF SEBEWAING, MICHIGAN.

STOVEPIPE-THIMBLE.

SPECIFICATION forming part of Letters Patent No. 722,607, dated March 10, 1903.

Application filed August 20, 1901. Renewed July 11, 1902. Serial No. 115,219. (No model.)

To all whom it may concern:

Be it known that I, ADOLPH MUELLER-WIESS, a citizen of the United States, residing at Sebewaing, in the county of Huron and State of Michigan, have invented new and useful Improvements in Stovepipe-Thimbles, of which the following is a specification.

My invention has relation to improvements in stovepipe-thimbles; and the object is to provide an article or device of the kind named which is simple in construction and efficient in effecting the purpose and which may be conveniently packed for transportation within the least possible space.

With these objects in view the invention consists in a new and improved article of manufacture having novel constructions and combinations, as will be hereinafter fully specified, and particularly pointed out and distinctly claimed.

I have fully and clearly illustrated my invention in the accompanying drawings, wherein—

Figure 1 is a perspective view of my improved stovepipe-thimble complete. Fig. 2 is a longitudinal sectional view showing the end of a stovepipe - section inserted in the thimble. Fig. 3 is a detail perspective view of the thimble with the clamping bar and bolts removed.

Referring to the drawings, A designates the body of the thimble, which consists of a suitable strip of sheet metal formed into a pipe or cylinder and left open at its meeting edges, which are adapted to lap or overlie each other and are provided with suitable registering apertures 1. The outer end of the thimble is formed with an annular flange 2, and the inner end for a proper distance is tapered, as at 3, to enter and wedge within the pipe-hole of the chimney or flue. The part 3 is preferably crimped or corrugated, so as to take firmly in the pipe-hole in the flue.

4 designates a clamping and holding plate or bar which is laid over the meeting and lapped edges of the thimble, with its inner end coincident with the outer or base line of the taper and extending at the front end beyond

the edge of the thimble, as at 5, to overlie the surface of a pipe-section which may be 50 inserted in the thimble. This plate or bar 4 is provided with apertures 6, registering with those in the lapped edges of the body of the thimble, and through these registering apertures are projected headed bolts 7, entered 55 from the inner side and provided with fastening-nuts 8, whereby the lapped edges of the thimble are clamped together and the bar also held in place. In the projecting end of the bar 4 is made a threaded hole in which 60 engages a threaded fastening or holding pin 9, the point of which bears on the surface of the inserted pipe, as indicated in Fig. 2 of the drawings, and holds the thimble and the pipe locked together. 65

The parts may be assembled or secured together for use by pressing the meeting edges of the thimble to make the lap, when the bolts can be passed through the apertures in the lapped edges. The bar then can be placed 70 in position and the fastening-nuts applied. The holding-pin can then be inserted in the projecting end of the bar, and the device is ready for use. The device is then forced into the flue or chimney pipe-hole, the stovepipe 75 inserted in the thimble, and the holding-pin screwed down to bear on the pipe.

When the barrel of the thimble is in the condition indicated in Fig. 3 of the drawings, with the edges free, it will be perceived that 80 a number of them may be nested or telescoped and occupy but little space and in which condition they can be conveniently transported.

What I claim is—

1. In a stovepipe-thimble, the combination 85 of a split cylinder of sheet metal, having its edges overlapped, a clamping member arranged over said overlapped edges, said member having a portion extending beyond the end of the cylinder, means carried by said 90 clamping member adapted to engage a pipe-section inserted in the thimble, and means passing through said overlapped edges and said member for securing them together.

2. In a stovepipe-thimble, the combination 95 of a split cylinder of sheet metal having its

inner end portion tapered and longitudinally corrugated and its edges overlapped, a clamping - strip arranged over said overlapped edges with a portion thereof extending beyond the end of the cylinder to overlap a pipe-section, fastening means passing through said overlapped edges and the clamping-strip to hold them together, and a threaded pointed pin projected through the projecting end of

the clamping-strip to engage a pipe-section to and hold the thimble thereon.

In testimony whereof I affix my signature in presence of two witnesses.

ADOLPH MUELLERWIESS.
